UNITED STATES PATENT OFFICE.

CLAUDE F. UTTERBACK, OF MOORESVILLE, INDIANA.

MAIL-BOX.

1,128,919.

Specification of Letters Patent.

Patented Feb. 16, 1915.

Original application filed December 24, 1912, Serial No. 738,446. Divided and this application filed January 20, 1914. Serial No. 818,214.

To all whom it may concern:

Be it known that I, CLAUDE F. UTTERBACK, a citizen of the United States, and a resident of Mooresville, in the county of 5 Morgan and State of Indiana, have invented certain new and useful Improvements in Mail-Boxes, of which the following is a specification.

My present invention relates to mail 10 boxes, and is a division of my co-pending application, No. 738,446, filed December 24, 1912, my more particular purpose being to provide a device of this type having improved means for safe-guarding mail 15 placed in the box.

Reference is made to the accompanying drawing forming a part of this specification in which like letters indicate like parts.

Figure 1 is a perspective view of my improved mail box complete, the movable parts being in the positions they normally occupy when the box is closed; Fig. 2 is a vertical section taken through the front portion of the box, substantially on line 25 2-2 of Fig. 1, and Fig. 3 is an elevation of the upper portion of the box in Fig. 1, with the letter door open.

A casing 8 constitutes the body of the mail box and is provided with a swinging door 30 9 which I designate as the main door. This main door is hinged upon a rod 10 extending across the lower end of the body 8 and is provided with integral portions struck up to engage the rod as seen in Fig. 2 and with 35 a portion 11 integral with it and extending below the bottom of the casing 8 and bent backwardly as indicated at the bottom of Fig. 3. When the main door 9 is swung open upon the hinges 10 as a center, the 40 portion 11 lodges against the bottom of the box and serves as a brace for supporting the door and consequently a limiting stop to prevent the door from swinging beyond a predetermined angular position.

The casing is mounted upon a post 12 shown fragmentarily in Fig. 1. A small door 13 is by aid of hinges 14 mounted upon the main door 9 and is provided with a knob 15. This small door is normally 45 closed as indicated by dotted lines in Fig. 2 and for this purpose is provided with tension springs 10^a. Because of its office, I

designate the door 13 as a letter door. It is opened by simply swinging it downward, as indicated by full lines in Fig. 2 and 55 closed by swinging it upward.

Within the casing 8 is a mail holder 16 having substantially the form of a weight and cut away on one side so that one of its edges 17 (see Fig. 2) is considerably lower 60 than its top. This arrangement is merely for facilitating the removal of letters or other mail which may be contained within the mail holder. A bracket 18 carried by the main door 9 supports the mail holder in 65 position.

The main door 9 is provided with a letter slot 19 through which letters may be thrust into the casing 8 and into the mail holder 16. Mounted upon the top of the casing 8 70 is a small bracket 20, and engaging the latter is a piece of wire 21 bent spirally around the bracket which thus serves as a journal. The wire 21 is provided with a portion 22 extending below the bracket. The piece of 75 wire 21 is also provided with a portion 23 extending upwardly and forwardly and carrying a leaf 25 of sheet metal. A weight 24 is also mounted upon the portion 23. The parts just mentioned are so arranged that 80 when the main door is swung open the portion 22 of the wire 21 is moved angularly outward and upward so that the wire member is tilted. The weight 24 is rocked backwardly and the leaf 25 is raised. This leaf 85 is observable from a distance and serves as a target for indicating the condition of the box. It ordinarily indicates that mail is in the box, for the reason that the box has been opened by the postman incidental to 90 the deposit of mail. The weight 24 maintains the target in either of its two positions in which the target may be placed.

Mounted upon the inner face of the door 9 is a lock casing 25^a which carries locking 95 mechanism as described and claimed in my copending application above referred to, and which controls the opening of the main door 9, it being understood that the letter door 13 may be freely opened and closed 100 wherever desired.

The mail box above described will be at once simple and inexpensive and yet constitute a safe repository and one which may

be easily and quickly opened and closed. Mail placed therein will be cared for and held so that when the main door is lowered and supported by its piece 11, the mail may 5 be readily withdrawn.

Having now thus described my invention, what I claim as new and desire to secure by Letters Patent is as follows:—

1. A mail box comprising a casing, a door 10 for opening and closing said casing, said door being mounted to swing outwardly at an angle from said casing, a bracket carried by said door, and a mail support engaging said bracket, said mail support consisting of a triangular receptacle disposed 15 flat-wise against the door and cut away on one side next to the door to facilitate the

removal of mail from said mail support when said door is swung outwardly.

2. A mail box comprising a casing open at 20 its front and having a rod extending across the lower portion of the front thereof, and a door having integral portions thereof, adjacent its lower end, struck up and engaging a rod to form a hinged connection between the door and the casing, said door having an angular lower edge below the hinged connection and movable to engage the casing base when the door is open, substantially as described.

CLAUDE F. UTTERBACK.
